Norman E. Lauterbach, Newark, N. Y., and Walter D. Teague, Annandale, N. J., assignors to Ritter Company, Inc., Rochester, N. Y., a corporation of Delaware

Application September 15, 1951, Serial No. 16,656

Term of patent 14 years

(Cl. D15—3)

To all whom it may concern:

Be it known that we, Norman E. Lauterbach and Walter D. Teague, both citizens of the United States, residing at Newark, in the county of Wayne and State of New York, and Annandale, in the county of Hunterdon and State of New Jersey, respectively, have jointly invented a new, original, and ornamental Design for a Combination Dental and Medical Operating Chair, of which the following is a specification, reference being had to the accompanying drawing, forming a part thereof.

Fig. 1 is a perspective side view of a combination dental and medical operating chair embodying our new design.

Fig. 2 is a perspective view of the same, as seen from the rear thereof.

We claim:

The ornamental design for a combination den-

tal and medical operating chair, substantially as shown.

NORMAN E. LAUTERBACH.
WALTER D. TEAGUE.
